UNITED STATES PATENT OFFICE.

CHARLES K. HARRIS, OF NEW YORK, N. Y.

CARD HOLDER.

Application filed May 20, 1924. Serial No. 714,718.

To all whom it may concern:

Be it known that I, CHARLES K. HARRIS, a citizen of the United States, residing at New York city, in the county of New York and State of New York, have invented new and useful Improvements in Card Holders, of which the following is a specification.

This invention relates to improvements in card holders, and has for its primary object, the provision of a device adapted to receive a deck of playing cards, and so constructed that only a single card may be withdrawn therefrom at one time.

Another object of the invention is to provide a card holder for use in the playing of such games as pinochle wherein each player draws a single card from the deck after each play, and which card may be drawn in such manner that the opposing players cannot see the underside of the same.

A further object resides in the construction of a playing card holder which includes a means for supporting the trump card when playing games which require the trump card to be exposed.

A still further object is to provide a device of the type mentioned which is simple in construction, cheap of manufacture and highly ornamental in appearance.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a perspective view of my improved card holder.

Figure 2 is a front elevation of the same.

Figure 3 is a vertical sectional view on the line 3—3 of Figure 1.

Figure 4 is an enlarged vertical sectional view on the line 4—4 of Figure 2.

Referring more particularly to the drawing, the reference numeral 10 designates my improved holder in its entirety and which includes a casing 11, mounted upon a relatively heavy base 12, which base prevents accidental movement of the device when drawing a card from the holder in the manner to be described. The casing 11 is open at its top as at 13 and at its front as at 14. The top of the casing is bent to form a marginal flange 15 against which the cards are pressed in a manner also to be explained,

The sides of the casing at the front thereof, are provided with inwardly bent ears 16, the tops of which terminate a slight distance below the ends of the flange to provide slits or openings 17 of a thickness to permit a single card to pass.

In Figures 1, 3 and 4 there is shown a plurality of cards A arranged in stack formation within the casing, so that the top card is in horizontal alignment with the slits 17. The ears 16 also serve to prevent outward movement of the cards other than the top card, thereby assuring that a player may only draw a single card at one drawing. In order to force the top card into register with the openings or slits, I provide a means 18 which includes a plate or follower 19, hinged at the rear of the casing as at 20. The pivot pin 21 of the hinge extends the entire width of the casing and receives two sets of coils 22 of a spring 23. The part 24 of the spring intermediate the coils extends forward beneath the plate, while the free ends of the spring abut the rear wall of the casing. It will be seen that the tension of the spring is greater when the plate is in a position nearest the bottom of the casing, but sufficient tension is always provided for holding the top card into register with the slits. The front of the follower or plate is formed with finger pieces or manipulating elements 25 for permitting the follower to be manually depressed when inserting the deck of cards into the holder.

From the foregoing description, it will be seen that the cards are withdrawn from the casing by sliding the top card through the slits, and as the cards are ejected, the stack gradually becomes thinner. As the cards are drawn, the follower will force the next card against the flanges and it will be noted that the pressure exerted by the spring is always applied on the front end of the card by reason of the hinge plate or follower co-acting with the cards at this particular point. It is of course understood that the holder is built in such manner that the plate is never below the horizontal axis of its pivot after the cards are inserted, so that the pressure is always at the front edge of the cards.

When playing such games as pinochle, it is customary to turn up the trump, and for supporting this card in a turned up position, I employ a spring clip 26 mounted on the rear wall of the casing as clearly shown

in Figures 1 and 2. One edge of the card is slipped into the clip so that the same may be exposed to the view of the players.

While I have specifically mentioned the holder for use in connection with playing cards, it is to be understood that the size and design may be altered to accommodate tickets or other cards without departing in any way from the spirit of the invention.

10 What is claimed as new is:—

1. A card holder comprising a casing having its front opened, flanges extending inwardly from the walls of said casing, portions extending inwardly from the side walls of the casing at the open front and spaced from the flanges to form slits, and means for holding the top card of a plurality of cards in register with the slits, said means including a plate hingedly mounted at the rear of said casing, and a spring for forcing said plate toward said flanges.

15 2. A card holder comprising a casing having its front opened, flanges extending in-

wardly from the walls of said casing, portions extending inwardly from the side walls of the casing at the open front and spaced from the flanges to form slits, and means for holding the top card of a plurality of cards in register with the slits, 25 said means including a plate hingedly mounted at the rear of said casing, and a spring for forcing said plate toward said flanges, and means for supporting a card in exposed condition after being drawn 30 from said casing.

3. A card holder comprising a casing formed with a slit at the front thereof, and means for holding the top card of a plurality of cards in stack formation in register 40 with the slit whereby only a single card may be withdrawn at one time, said means including a hinged plate, and a spring for forcing the free end of said plate into contact with the front edge of the stack of 45 cards.

In testimony whereof I affix my signature.

CHARLES K. HARRIS.
